CLAIM

The ornamental design for blades for pruning shears, as shown and described.

DESCRIPTION

FIG. 1 is a top front left perspective view of blades for pruning shears;

FIG. 2 is a front elevational view thereof;

FIG. 3 is a left elevational view thereof;

FIG. 4 is a rear elevational view thereof;

FIG. 5 is a right elevational view thereof;

FIG. 6 is a top plan view thereof; and,

FIG. 7 is a bottom plan view thereof.

The broken lines showing various portions of exemplary pruning shears are for illustrative purposes only and form no part of the claimed design.
